UNITED STATES PATENT OFFICE.

THOMAS N. BROWN, OF FORT WAYNE, INDIANA, ASSIGNOR TO UTENSILS COMPANY, OF FORT WAYNE, INDIANA, A CORPORATION OF INDIANA.

IRONING MACHINE.

Application filed October 23, 1925. Serial No. 64,317.

This invention relates to improvements in ironing machines of that class generally known in domestic use and in which a revolving feed roller is used in conjunction with a revoluble heated smoothing roller, and the object thereof is to provide in an ironing machine a feed roller and gear mechanism therefor in conjunction with an adjustable friction member so arranged that the feed roller, when thrown in gear will move into bearing relation with the smoothing roller with more or less force accordingly as the friction member is adjusted, and so that when the feed roller is thrown out of gear it will automatically move from operative position of its own weight leaving a clearance between the rollers. Another object of the improvement is to construct the gear mechanism by which the feed roller is actuated so as to permit of a wide range of movement of the feed roller from the smoothing roller while in gear in order to accommodate thick pieces of goods between the rollers.

These objects are accomplished by the construction illustrated in the accompanying drawings, in which:

Fig. 1 is a perspective view of an ironing machine embodying the present invention;

Fig. 2 is a side view of the feed roller with its support and the friction member;

Fig. 3 is a detail view of the expanding band;

Fig. 4 is an end view projected from Fig. 2;

Fig. 5 is a side view of a yielding prop for the bracket in which the feed roller is mounted;

Fig. 6 is a front end view of the head of the machine, the feed roller and its supporting bracket being omitted; and

Fig. 7 is a plan view projected from Fig. 6 and in which is included a fragmentary part of the feed roller and its support.

The characters appearing in the description refer to parts shown in the drawings and designated thereon by corresponding characters.

The machine here shown as an example of the invention comprises a stand 1 having at its upper end a gear case 2 in which is rotatably mounted two drive shafts 3 and 4 that are spaced apart and extend through the front of the case 2 in parallel relation with each other, and which shafts are rotated, in

the directions indicated by arrows respectively, by any suitable gearing (not shown) contained in the gear case, the gearing being actuated by a pulley 5.

A cylindrical smoothing roller 6 has fixed connection at one end with the drive shaft 3 and is supported at its opposite end by a stub-shaft 3' that extends in alinement with the drive shaft 3 and is supported by an overhanging bracket 6' on the gear case 2, said smoothing roller being rotated by the drive-shaft 3. A hood 7 positioned over the smoothing roller and spaced therefrom is supported by said bracket and tends to conserve the heat of said roller. The roller may be heated electrically or by a gas burner in the usual manner, means for which are not herein disclosed as such means are not peculiar to the present invention and may be of any suitable type.

The particular features of the invention consist in the means for imparting movement from the drive shaft 4 to the feed roller and for throwing the feed roller into and out of gear, and the means by which the feed roller is applied with more or less pressure to the smoothing member.

Extending from the front of the gear case, parallel with said drive shafts is a stationary supporting rod 8 upon which is loosely mounted a tube 9 having at each end thereof an arm 10 and 11 respectively, said tube and arms constituting a rocking member.

A prop 8' is secured at one end to the stand 1 and at its opposite end to the rod 8, there being an opening 9' in the tube 9 of the rocking member to admit of connection of the prop with the rod.

In the outer ends of the arms is revolvably mounted a feed shaft 12, and upon which shaft is mounted a feed roller 13 having thereon a covering 14 of suitable padding material. Upon the inner end of the shaft 12 is fixed a pinion 15 that is actuated in the manner hereinafter described.

The inner end of the feed roller 13 has a flanged spider 16, and within the flange of said spider is loosely positioned an expansion band 17, each end of which has an inwardly extending lug 18, which lugs are spaced apart. The arm 10 has a pendant branch 19 in which is mounted an oscillatable member 20 that extends between the lugs 18 on the expansion member and is so shaped that said lugs are spread apart more

or less according to the extent the oscillatable member is adjustably turned. To the outer end of the oscillatable member is secured a lever 21 that is connected with a rod 22 which extends loosely through a lug 23 on the arm 10, the rod being threaded to receive an adjusting wheel 24. The wheel bears against said lug and the oscillatable member is actuated accordingly as said wheel is turned and the band 17 is expanded so as to bear with corresponding force against the flange of the spider. The oscillatable member also prevents turning movement of the expanding band with the spider which is part of and revolves with the roller 13.

10 A series of pegs 25 on the arm 10 serve as stops to prevent outward displacement of the expanding band.

As a means to stop the downward swing 20 of the feed roller when thrown out of gear and to partially counterbalance the weight thereof, a yielding prop is provided and consists of a plate 26 secured by a pivot 27 to the lower end of the branch 19, and has at 25 each end a perforated lug 28 through which loosely extends a rod 29, one end of which is pivoted to a collar 30 that is fixed on the brace 8'. Upon the rod 29, between the lugs 28 is disposed a compression spring 31, one 30 end of which bears against the outermost lug, and the inner end of which bears against a washer 32 that is engaged by a cotter pin 33 in the rod so that the plate has movement on said rod in one direction restrained by said spring. The strength of the spring 31 is such as to counteract the major portion of the weight of the roller and the assemblage of parts connected therewith which weight causes the rocking member, when the feed roller is out of gear, to swing downwardly and compress said spring. Also, upon the rod 29 adjacent the roller 30 is provided a cushion or spring stop 34 that serves to limit movement of the plate 26 on said rod and consequently the downward swing of the rocking member and roller mounted thereon.

Upon a pivot 35 on the gear case is mounted a swinging plate 36 having thereon a stud 37 upon which is loosely mounted a pinion 38 that is actuated by a driving pinion 39 fixed on the end of the shaft 4 when said plate 36 is in operating position and is disengaged therefrom when said plate is swung out of operating position. Upon the stud 37 is also loosely mounted a drag pinion 40 that is actuated by pins 41 projecting from the pinion 38 into openings 42 in the drag pinion, said openings being sufficiently larger than said pins as to admit of play between the pinions 38 and 40 in the direction of rotation. A tension spring 43 is secured at one end to the drag pinion and at its other end to one of the pins 41 and acts to take up the play between said pinions.

The drag pinion 40 has actuating relation

with the pinion 15 on the roller shaft 12 when the plate 36 is in operating position, and is disengaged therefrom when said plate is moved out of operating position. The play between the pinion 38 and 40 permits 70 ready articulation of the teeth of the pinions 38 and 39, and of the pinions 40 and 15 when moved into engaging relation as the plate 36 is swung into operating position. A tension spring 44 has connection at 75 one end with the case 2 and at its opposite end with the plate 36, and tends to hold said plate out of operating position, and a toggle 45, operated by a handle 46 is provided to move the plate 36 into and hold it in operating position opposed by the action of the spring 44.

80 A supplementary means of moving the plate 36 into operating position is provided, and consists of a block 47 mounted upon a pivot 48 on the case 2, which plate has pivoted thereto a finger 49 that bears against a projection 50 on the plate 36 and lifts the plate into operating position when the block 47 is raised. The finger 49 has a jaw 51 90 that has contact with the adjacent end of the block so that its swinging movement in one direction relative to said block is thereby limited. The block 47 rests upon a lever 52 that is actuated by a pedal member 95 53 arranged in the stand to be depressed by the foot of the operator. When the pedal is depressed, the plate is moved into operating position through the expedient of the toggle formed by the block and finger, and when the pedal is released the plate is moved out of operating position by the spring 44. Thus, the feed roller may be thrown into and out of gear by foot operation.

100 In the operation of the invention continuous motion is applied to the pulley 5 by any suitable means such as an electric motor 54 which may be conveniently mounted in connection with the stand 1 and controlled by a switch 55 on the case 2, and the smoothing 105 member is thereby rotated accordingly. Heat is then applied to the smoothing roller, and the goods to be ironed are introduced between the feed roller and smoothing member in the usual manner. By depressing the pedal 46 the plate 36 is moved into operating position so that the pinion 38 meshes with the pinion 39 and the pinion 40 becomes enmeshed with the pinion 15 on the roller shaft causing the feed roller to rotate. By manipulating the adjusting wheel 24 the expanding member is caused to bear against the flange of the spider in the feed roller with more or less force according to the adjustment of said wheel and the rotation of the feed roller is thereby frictionally resisted so that the torque of the drag pinion 38 which is meshed with the pinion 15 on the feed roller shaft elevates the pinion 15 110 and parts associated therewith on the rock- 115

ing member as well as imparts rotary movement to said pinion and feed roller operatively connected therewith. In this manner, while rotating, the feed roller is brought into bearing contact with the smoothing member more or less forcibly according to the adjustment of the hand wheel 24, and the pressure applied to the goods passing between the feed roller and smoothing roller may be adjustably varied at will. However, varying thicknesses of the goods passing between the feed roller and the smoothing member does not materially alter the pressure applied to the goods as the 15 rocking member swings downwardly to accommodate the goods according to its thickness, and therefore, the action of the smoothing roller upon the goods is maintained with uniformity irrespective of the thickness of the goods.

A feature of the invention is in the manner in which the gears, through which movement is imparted to the feed roller, are supported and by which parallelism of their 25 axis is maintained, which maintenance is essential to the proper working and durability of the gears. Also, the present invention contemplates an improved mounting for the rocking member whereby the feed roller on said member is sustained with 30 its axis in proper parallelism with that of the driving gear.

What I claim is:—

1. In an ironing machine having a smoothing member and a supporting stand including a gear case and a gear mechanism for driving the smoothing member, a driving pinion actuated by said mechanism; a plate pivotally supported on said case; a pair of 40 axially aligned gears in supported connection with said plate, one of which gears is engageable with said driving pinion and being provided with means for limited rotative movement relative to its companion gear; a spring actuating said plate tending 45 to disengage said pair of gears from said driving pinion; a toggle member provided with means for limited toggle movement operable to move said plate against the tension of said spring to throw said gears into 50 engaged relation with said driving pinion; a pedal mechanism for actuating said toggle member; a support including a rod and prop therefor connected together each having 55 fixed connection with said stand; a swingable frame on said rod; a feed roller including a shaft therefor mounted in the frame, said shaft having a gear engageable with said companion gear when the driving pinion 60 is engaged with the other of said pair of gears; a flanged member in said feed roller; an expansion member floating in said flange member; adjusting means supported in said frame having actuating engagement 65 with said expansion member; a yielding

prop in connection with said swingable frame having a spring operable to partially but not completely counterbalance said frame and having a second spring operable to limit downward movement of said frame; 70 and a hand operated toggle having actuating relation with said pivotally mounted plate independent of the former toggle member.

2. In an ironing machine having a smoothing member and a feed roller in co-operable relation therewith, a swingable member supporting said feed roller; an expansion member floating in said feed roller; an adjusting means supported in said frame having 80 engagement with said expansion member; a yielding prop in connection with said swingable frame having a spring operable to partially but not completely counterbalance said frame and having a second spring 85 independent of the former spring operable to limit downward movement of said frame; a gearing operable to rotate said smoothing member and feed roller; means to raise said feed roller into contact with said smoothing member with more or less force accordingly as said expansion member is adjusted; and means for throwing said gearing out of engagement with said feed roller.

3. In an ironing machine having a smoothing member and feed roller in co-operable relation therewith, a swingable member supporting said feed roller; a floating expansion member in said feed roller; an adjusting means on the frame engaging the expansion member; a yielding prop operable to partially but not completely counterbalance said frame; a gearing operable to rotate said feed roller; means to actuate said frame so as to raise said feed roller into contact with 100 the smoothing member with more or less force accordingly as said expansion member is adjusted; and means for throwing said gearing out of engagement with said feed roller.

4. In an ironing machine having a smoothing member and feed roller in co-operable relation therewith, a frame supporting said feed roller and having limited swinging movement operable to move the feed roller 105 into engagement with the smoothing member; a floating expansion member in said feed roller; an adjusting means on the frame engaging the expansion member; a gearing operable to rotate said feed roller; means to actuate said frame more or less positively according to the adjustment of the expansion member; and means for throwing said gearing out of engagement with said feed roller.

5. In an ironing machine having a smoothing member and feed roller in co-operable relation therewith, a swingable frame supporting said feed roller; means operable to raise said feed roller into operable relation 115 120 125 130

- 4
- with said smoothing member; a yielding prop in connection with said frame having a spring operable to partially but not completely counterbalance said frame and having a second spring operable to limit downward movement of said frame; means having frictional engagement with said feed roller operable to actuate said frame; and a gearing for actuating said feed roller.
10. 6. In an ironing machine having a smoothing member and feed roller in co-operable relation therewith, a frame supporting said feed roller and having limited movement; means operable to move said feed roller into engagement with the smoothing member; a yielding prop in connection with said frame operable to partially but not completely counterbalance said frame; means actuated by said feed roller operable to raise said frame; and a gearing for actuating said feed roller.
7. In an ironing machine having a smoothing member and feed roller in co-operable relation therewith, a support for said feed roller having limited movement; means operable to lift said feed roller into engagement with the smoothing member; means actuated by said feed roller operable to actuate said support; a driving pinion; a second pinion mounted in connection with the feed roller; a motion transmitting gearing mounted so as to have movement in an arc of a circle and to have engagement with said pinions; and means for moving said gearing into and out of engagement with said pinions.

In testimony whereof I affix my signature.
THOMAS N. BROWN.
